VEHICLE WHEEL BRUSH MOUNT

Earl Dallas Smith, 6202 E. Sage Drive, Scottsdale, Ariz.
85251, and John K. Bunch, 6731 N. 16th St., Phoenix,
Ariz. 85016

Filed Dec. 18, 1967, Ser. No. 9,821

Term of patent 14 years

(Cl. D49—12)

Fig. 1

Fig. 4

Fig. 5

Fig. 3

Fig. 2

FIG. 1 is an elevational view of a vehicle wheel brush mount showing our new design.

FIG. 2 is an elevational view thereof viewed in the direction opposite FIG. 1.

FIG. 3 is a top plan view thereof.

FIG. 4 is an elevational view thereof as seen when looking from left-to-right in FIGS. 2 and 3.

FIG. 5 is an elevational view thereof as seen when looking from right-to-left in FIGS. 2 and 3.

Dominant features of our design reside in portions shown in full lines.

We claim:

The ornamental design for a vehicle wheel brush mount, substantially as shown and described.
